(57) **CLAIM**

I claim the ornamental design for a rail jig with level and rule, as shown and described.

DESCRIPTION

FIG. 1 is a perspective view of a rail jig with level and rule, showing my new design;

FIG. 2 is an exploded perspective view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is an enlarged left-side elevational view thereof, the right-side elevational view being a mirror image thereof. The broken lines in the figures depict environmental matter that forms no part of the design.
